UNITED STATES PATENT OFFICE.

JOHN Q. C. SEARLE, OF CINCINNATI, OHIO.

CAR-WARMER.

SPECIFICATION forming part of Letters Patent No. 236,849, dated January 18, 1881.

Application filed May 28, 1880. (No model.)

To all whom it may concern:

Be it known that I, JOHN Q. C. SEARLE, of Cincinnati, in the county of Hamilton and State of Ohio, have invented certain new and useful Improvements in Railway-Car Warmers, of which the following is a specification.

My invention is in the nature of an improvement in that class of railway-car warmers which employs a circulating hot-water apparatus in the lower portion of the car, with the heating or radiating pipes usually placed under the car-seats; and it consists in the construction and arrangement of a short circulating-circuit, in connection with a combined expansion-chamber and water-reservoir, which, when the car is temporarily out of use, enables the maintenance, at any desired temperature, with a small expense of fuel, of a quantity of water sufficient to fill all the circulating and radiating pipes, and also permits of the use of ordinary water in the heating-coil and in the circulating-pipes without the liability to freezing, as will be fully explained hereinafter.

In the accompanying drawings, Figure 1 is a general view of the interior of a car, showing the arrangement of the several elements constituting my invention; and Fig. 2 is a sectional view of one of the cocks used in the system of circulating-pipes.

Similar letters of reference indicate similar parts.

A is the body of an ordinary passenger rail-way-car, in one end of which I place any suitable heating-stove, B, containing an ordinary water-heating coil, C, the upper and lower legs (outlet and inlet) of which are projected horizontally through the fire-pot and shell of the stove, as shown in Fig. 1, to connect with the circulating-pipes, to be described.

F is a cylindrical expansion-chamber and water-reservoir, provided with water-testcocks f f and a low-pressure gage, f'.

E E are the leading-pipes, through which the heated water passes from the upper leg of the coil C to the radiators, placed under the seats of the car. The radiators are not shown in the drawings, as they constitute no part of my invention. The upper leg of the coil C connects with the pipe E, near the expansion-chamber F.

D D are the return-pipes through which the

cooled water is conveyed back to the heating-coil C after it has passed the circuit of the radiators.

D' is a pipe connecting the expansion-chamber F with the lower leg of the coil C.

d is a two-way cock of peculiar construction, (shown in detail in Fig. 2,) which, by placing it in proper position, connects the lower leg of the coil C either with the pipe D or with the pipe D'.

e is a common stop-cock, situated in the descending pipe E, near its junction with the upper leg of the coil C, by means of which the expansion-chamber and water-reservoir F are connected with or disconnected from the circulating-pipes E E.

d' is a stop-cock in the pipe D', through which the water in the pipes E E and D D and in the radiators may be drawn off when necessary.

G is a rising pipe, which is connected with the top of the expansion-chamber and water-reservoir F and passes up through the roof of the car.

g is a funnel, through which water is introduced into the expansion-chamber and water-reservoir F.

g' is a safety-valve placed on the upper end of the pipe G, for the purpose of relieving the expansion-chamber and water-reservoir of any excess of pressure which may occur therein.

g² is a stop-cock, which connects the funnel g with the rising pipe G and remains closed while the apparatus is in use.

g³ is a small stop-cock, to relieve the expansion-chamber and water-reservoir F of air while being charged with water.

H is a divided water-tank, for toilet purposes, one compartment of which contains cold water, and the other compartment of which contains water heated to an agreeable temperature by means of the small coil H', connected by the pipe h' with the leading pipe E, and by the pipe h with the return-pipe D. An air-space is provided between the two compartments of the tank H to prevent the heating of the water in the cold-water compartment.

I is a pipe or casing, connected at the lower end with the pipe K, and provided at the upper end with a cup or seat, i. The pipe K con-

nects with the expansion-chamber and water-reservoir F, near the lower end thereof, and passes through the shell and fire-pot of the stove B. At the junction of the casing I and the pipe K a lifting water gate or plug will be placed, connected, by means of a chain or wire, with a ball seated in a cup located at a suitable point. If the ball is lifted or tilted from its seat it withdraws the plug from its socket 10 and permits the water in the expansion-chamber and water-reservoir F to rush through the pipe K into the stove B to extinguish the fire.

J is a rod actuated by the hand-lever j, to which the arms of the cocks d, d', and e are pivoted, the arms or levers on the cocks being so arranged that when the hand-lever j is drawn up the cock e is open, the cock d' closed, and the cock d set to connect the pipe D with the lower leg of the coil C; and when the hand-lever j is forced down the cock e is closed, the cock d' is opened, and the cock d set to connect the pipe D' with the lower leg of the coil C.

The operation of the apparatus is as follows: Assuming the radiators and all the pipes and the coil void of water, as well as the expansion-chamber and water-reservoir F, the hand-lever j up, and the cocks d, d', and e in the position first described, the cocks g² and g³ open, then water is poured into the funnel 30 g until all the radiators, and the pipes E E, and the pipes D D, and the coil C, and expansion-chamber and water-reservoir F are all entirely filled with water. The cocks g² and g³ are then closed, and the upper try-cock, f, 35 opened, and the water above this cock drawn off, the space thus formed being to accommodate the dilatation of the remaining water as it becomes heated. The apparatus now being in readiness for the application of heat to the coil C, the heating of the water in the coil causes the hotter water to rise and pass out through the upper leg of the coil into the leading-pipe E E, and then circulate through the radiators, thereby warming the car, and 40 finally to return cooled, through the return-pipes D D, to the lower leg of the coil C, there to be again heated and traverse indefinitely the same route from the upper leg of the coil through the leading-pipes and radiators, and 45 back to the coil by the return-pipes. This is what I term "the long circulating-circuit."

If the entire system of pipes were completely filled with water and no escape was provided, then the natural dilatation of the water by 50 the elevation of temperature would burst the expansion-chamber and water-reservoir F, or the pipes, or the connections, and thus unfit the apparatus for use. To avoid an occurrence of this nature space for the expansion 55 in volume of the water is provided in the expansion-chamber and water-reservoir F, as already described.

The leading-pipe E being shown as penetrating the bottom of the expansion-chamber 60 and water-reservoir F, and the expansion-chamber and water-reservoir F as connected with the leading-pipe E, but forming no part

of the circulating system of pipes, it follows that no transfer of water from the expansion-chamber and water-reservoir to the circulating system, or from the circulating system to the expansion-chamber and water-reservoir, can take place during the natural operation of the apparatus, save as leaks may occur in the radiators, when the water thus lost would be supplied from the expansion-chamber and water-reservoir F, and by the dilatation of the water in the coil and system of circulating-pipes, when the excess of water would pass up the vertical pipe E into the expansion-chamber and water-reservoir until the pressure subsisting in the expansion-chamber and water-reservoir shall equal (less the hydrostatic head) that of the pressure in the coil C and circulating-pipes E E and D D and in the radiators. Suppose, however, that the car containing the heater is temporarily out of use, and the weather is sufficiently cold to congeal the water in the circulating-pipes and in the radiators unless an active circulation of the 90 water is had by maintaining the usual condition of fire in the stove B, then, to avoid the necessity of a strong fire in the stove B, and at the same time to effectually prevent the congelation of the water in the circulating-pipes 95 and in the radiators, the hand-lever j is forced down until the cocks d, d', and e occupy the second position described—viz., the cock d' open, the cock e closed, and the cock d set to connect the pipe D' with the lower leg of the 100 coil C. The effect of this change is, first, to drain the leading-pipes E E, the radiators, and the return-pipes D D of the contained water; and, second, to connect the upper leg of the coil C with the expansion-chamber and 105 water-reservoir F through the upper portion of the vertical pipe E, to form what I term the "short circulating-circuit." The circulation then takes place in the coil C, the expansion-chamber and water-reservoir F, and the descending pipe D'. Under this condition, the 110 pipes E E and D D and the radiators being void of water, no freezing can occur.

The short circulating-circuit, having the expansion-chamber and water-reservoir F as a 115 part of the system, it is obvious that in a short interval of time the contents of the expansion-chamber and water-reservoir will be at a high temperature, and if the expansion-chamber and water-reservoir be of sufficient capacity to 120 furnish a full supply of water to the circulating-pipes E E and D D and the radiators, it is only necessary to draw the hand-lever j up and place the cocks d, d', and e in the first position described, when the entire contents of the expansion-chamber and water-reservoir F will 125 flow into the pipes E E, the radiators, and the pipes D D, and circulation in the long circulating-circuit will be re-established. The expansion-chamber and water-reservoir F will be 130 refilled in the manner heretofore described.

It will be observed that the expansion-chamber and water-reservoir F, while it serves simply as an expansion-chamber for the long cir-

culating-circuit, and may be of small capacity for this purpose, is for the purpose of the short circulating-circuit, preferably of sufficient capacity to furnish a full supply of water to the 5 circulating-pipes E E and D D and the radiators; and that while no circulation of the water contained in the expansion-chamber and water-reservoir F can occur when the long circulating-circuit is in use, that circulation does 10 occur in the expansion-chamber and water-reservoir when the short circulating-circuit is in use.

I am aware that the use of a short circulating-circuit in hot-water warming apparatus is 15 not used, and that several attempts have heretofore been made to adapt it to the requirements of practice, which attempts have been only partially successful.

Having described my invention, what I claim 20 is—

1. The combination, with the expansion-chamber and water-reservoir F, of the pipes E, leading from the said reservoir to the radiators of a hot-water warming apparatus for 25 railway-cars, the return-pipes D, and the heating-coil C, having its upper leg connected with the outflow-pipe E at a point intermediate of the reservoir and the radiators, and having its lower leg connected with the return-pipe D, 30 substantially as shown, and for the purpose set forth.

2. The combination, with the expansion-chamber and water-reservoir F, of the pipes

D' and E, provided with cocks d and e, and leading from said reservoir, and the coil C, arranged to open at the terminus of its upper leg into the pipe E, and to communicate at the extremity of its lower leg with the pipe D', substantially as and for the purpose set forth. 35

3. The combination, with the expansion-chamber and water-reservoir F, of the outflow-pipe E, extending from said reservoir to the radiators, the return-pipes D, the descending pipe D', communicating with the return-pipe and with the reservoir, the heating-coil C, communicating at its upper leg with the pipe E 40 at a point intermediate of the same and the radiators, and communicating at its lower end with both the return-pipe and the pipe D', the valve-cock e, intermediate of the radiators, and 45 the connection between the coil C and the outflow-pipe E, and the two-way cock d, arranged to establish communication either between the coil and the pipe D or the coil and the pipe D', substantially as set forth. 50

4. The combination of the cocks d, d', and e, hand-lever j, and connecting-bar J, for the purpose and as described. 55

In testimony whereof I have signed my name to the foregoing specification in the presence 60 of two subscribing witnesses.

JOHN Q. C. SEARLE.
